UNITED STATES PATENT OFFICE

JOSEPH BOROVITZ, OF NEW YORK, N. Y., ASSIGNOR TO JOSEPH BOROVITZ, INC., OF NEW YORK, N. Y., A CORPORATION OF NEW YORK

DESIGN FOR A COMBINED RECEPTACLE FOR SMOKERS' ARTICLES OR SIMILAR DEVICES

Application filed August 2, 1929, Serial No. 32,285, and in Germany May 21, 1929. Term of patent 3½ years.

To all whom it may concern:

Be it known that JOSEPH BOROVITZ, citizen of the United States and resident of New York city, in the county of New York and State of New York, has invented a new, original, and ornamental Design for a Combined Receptacle for Smokers' Articles, or Similar Devices, of which the following is a specification, reference being had to the accompanying drawings forming part thereof, in which—

Fig. 1 is a perspective view of a combined receptacle for smoker's articles or similar devices embodying my new design; and

Fig. 2 is a plan view thereof.

I claim:

The ornamental design for a combined receptacle for smokers' articles or similar devices as shown.

Dated, New York city, July 30, 1929.
